2 Sheets-Sheet 2

UNITED STATES PATENT OFFICE.

HENRY RYDER, OF NEW YORK, N. Y., ASSIGNOR TO WIRE FIBROUS PRODUCTS COMPANY, OF NEW YORK, N. Y., A CORPORATION OF NEW JERSEY.

SPINNING MACHINE.

Application filed November 29, 1922. Serial No. 603,992.

To all whom it may concern:

Be it known that I, HENRY RYDER, a citizen of the United States, residing at No. 371 West 46th Street, New York, in the 5 county of New York, State of New York, have invented certain new and useful Improvements in Spinning Machines; and I do hereby declare the following to be a full, 10 clear, and exact description of the invention, such as will enable others skilled in the art to which it appertains to make and use the same.

This invention relates to spinning machines of the type disclosed in my Patent 15 No. 1,113,489 of October 13, 1914.

The spinning machine disclosed in my prior patent, is adapted to be used for the purpose of spinning yarn, and, more particularly, for spinning fibres around a wire 20 core, thus forming a wire fibrous yarn. The fibres are spun around the wire in such a manner that they are all parallel to each other, and therefore adapted to carry an equal stress when the yarn is under tension.

25 The present invention relates to improvements in spinning machines of this type, whereby a multiple wire fibrous yarn may be made. This multiple wire fibrous yarn, which forms the subject matter of my co-pending application, Serial No. 603,993 filed November 29, 1922, has a core formed of a plurality of single wire fibrous yarns of the type made on the machine disclosed in my prior patent. This core may be said to consist of a plurality of parallel yarns and the

30 expression "parallel yarns", is intended to designate yarns that are not in intertwined relation. This core is covered with fibres spun around it in the same manner that the 40 fibres were spun around the single wire core of the yarn made by my original machine. More particularly, the present invention relates especially to the apparatus for feeding a plurality of wires, or single wire fibrous

45 yarns, to the conveyor of the spinning machine. By means of the present invention, it is possible to supply a plurality of wire or wire fibrous yarns to the flier of the spinning machine in such a manner that the 50 group of wire fibrous yarns revolve as a while at the same speed as the flier of the spinning machine, while the individual wire

fibrous yarns, lying parallel to each other, enter the nipper without being subjected to torsion or twist and are spun into a single 55 yarn the same as a single wire is spun into a single fibrous yarn as disclosed in my prior patent. Thus it is possible to make a multiple wire fibrous yarn having a core 60 consisting of a plurality of wire fibrous yarns parallel with each other, the core being made in such a manner that there is no torsional stress in the elements forming the core.

The principal object of the present invention is attained by providing a spool holder adapted to hold a plurality of spools from which single wire fibrous yarns, or wires, may be supplied, the spool holder being arranged in such a manner that it may 70 rotate about an axis at substantially right angles to the axes of the several spools. Each of the spools is rotated in the direction opposite to that in which the spool holder rotates, the mechanism for producing this motion 75 consisting of an eccentrically mounted wrist plate connected to the several spools by means of cranks or other equivalent means. Thus the group of yarns taken from the spools may be rotated as a whole by rotating 80 the spool holder and each individual yarn is prevented from twisting as the spool holder revolves, by means of the wrist plate which causes the spools to rotate with respect to the spool holder, in the direction opposite to the direction of rotation of the spool holder.

The present invention may be best understood by referring to the following detailed description which is to be considered in conjunction with the accompanying drawings, in which—

Fig. 1 is an elevation of a piece of single wire fibrous yarn as made by the spinning machine disclosed in my prior Patent No. 1,113,489.

Fig. 2 is a transverse section of the single wire fibrous yarn shown in Fig. 1;

Fig. 3 is an elevation of a piece of multiple wire fibrous yarn, showing the construction 100 thereof;

Fig. 4 is a transverse section of the yarn shown in Fig. 3;

Fig. 5 is a top plan view of the improved

spinning machine, part of the upper portion of the machine being cut away to show the lower portion of the machine;

Fig. 6 is a fragmentary view showing some of the details of construction;

Fig. 7 is a side elevation of the improved spinning machine;

Fig. 8 is a sectional view taken on line 8—8 of Fig. 7 showing the arrangement of 10 the eccentrically mounted wrist plate, and

Fig. 9 is a detailed drawing of a form of tensioning device which may be used in conjunction with the spools on the spool holder.

By referring to Figs. 5 and 7 of the drawings, it may be noted that the improved spinning machine is similar in many respects to that disclosed in my Patent No. 1,113,489. The machine is provided with a trumpet 52 for supplying fibres to the conveyor 51, the fibres being deposited on the conveyor 51 parallel to each other and to the direction of movement of the conveyor. The fibres pass along the conveyor to the nipper rolls 16 and 50. In my prior patent a single wire is passed along the top of the conveyor 51, whereas in the present invention a plurality of wire fibrous yarns are passed along the top of this conveyor. The yarns pass through a groove in the upper nipper roll 16 and over the divider 17. The fibres pass under the divider 17 and both the yarns and fibres enter the rotating sleeve 18 which spins the fibres around the yarns, thus forming a multiple wire fibrous yarn having a core consisting of a plurality of single wire fibrous yarns around which the fibres from the conveyor have been spun in such a manner that they all lie parallel to each other. As the finished yarn passes from the sleeve 18 it passes around capstan sheaves 19 and around guide sheaves 20 and onto the spool 21.

The raw fibres may be supplied to the trumpet 52 in the usual manner, and the conveyor 51, on which the fibres are deposited, may be driven in any suitable manner, for example, by means of the gears 30 and 31 which are driven by the sheave 29 which is, in turn, driven from the main drive shaft 2. The rotating sleeve 18 may be driven by means of a suitable gear train 36 which may also drive the capstan sheaves 19, as best shown in Fig. 6.

The flier 8 is caused to rotate by means of gears 6, 9 and 7, gear 7 being rigidly connected to the flier 8, gear 6 being connected to the shaft 5, and gear 9 serving as an idler. The spool holder 12, which will be described later, is caused to rotate in synchronism with flier 8 by means of suitable gears 11 and 13, the latter gear being fixed to the shaft 5. The spool 21, on which the finished yarn is wound, is fastened to a hollow shaft 23 which is loosely wound on a rod 22. This

spool 21 is caused to rotate by means of 65 gears 24, 25 and 26. Gear 26 is rigidly fastened to the sleeve 23, and gear 24 is driven by friction contact with gear 6, the gear 24 being held against gear 6 by means of a suitable spring 27. By this means, the spool 21 rotates at the proper speed to take up the slack in the yarn supplied to it. The spool 21 is caused to move back and forth on the rod 22 by means of a nut 49 mounted 70 on a screw 44 which carries right and left 75 handed screw threads.

Having described the general structure of the machine, the details of the spool holder mechanism may now be considered. As mentioned above, the spool holder 12 rotates in the same direction and with the same speed that the flier 8 rotates. The spool holder 12 comprises a disc or other suitable support, on which a plurality of 80 spools 14 are mounted. The yarns pass from the several spools to a suitable ring 35 for the purpose of bringing the yarns together to form a substantially compact core which passes along above the conveyor 51 in the 85 manner described above. 90

It is an established fact that if a wire or 95 yarn of any description is grasped firmly and unwound from a spool by pulling the wire or yarn straight away from the spool the wire or yarn is subjected to considerable torsion. The direction of this torsion depends upon whether the wire or yarn is taken from the underside of the spool or from the top. In order to relieve the wire or yarn from this torsion, it is necessary to either turn the spool from which the wire or yarn is taken, or to turn the wire itself. In either case this turning should be in such a direction that it tends to take the torsion or 100 twist out of the wire or yarn. 105

If the spools 14 were rigid on the spool holder, a considerable torsion or twist would be developed in each yarn when it is drawn from its spool. Thus, if the machine was constructed in this way, each yarn of the core would tend to turn about its own axis as the core was caused to rotate about its axis. In order to eliminate or neutralize this torsion it is necessary to rotate each of the spools 14 in the direction opposite to that in which the spool holder rotates. This is accomplished by means of the wrist plate 10 which is rotatively mounted on a fixed support 60. This support 60 is arranged in such a way that the wrist plate 10 is eccentrically mounted with respect to the axis of the spool holder. The wrist plate 10 is connected to the spools on the spool holder by means of cranks 61, the length of each crank being equal to the eccentricity of the support 60. The wrist plate 10 rotates with the spool holder and as these two members 110 115 120 125 rotate together, the spools are caused to ro-

tate in the opposite direction by virtue of the cranks 61 interconnecting the spools and the wrist plate.

The tensioning device shown in Fig. 9 consists of a guide roller or sheave 62 rotatably mounted on links 63 which are pivoted at the outer extremities thereof. The yarn from the spool 14 passes around the guide sheave 62, and the pressure of the sheave on the spool is automatically adjusted by the tension in the yarn. The object of this device is to prevent the yarns from unwinding from the spools too rapidly.

From the above description it should be apparent that a multiple wire fibrous yarn may be made by using a plurality of single wire fibrous yarns of the type shown in Fig. 1. The yarn of Fig. 1 consists of a wire core 65 around which fibres 66 have been spun in such a manner that they lie parallel to each other. The multiple wire fibrous yarn as shown in Fig. 3 consists of a core 67 composed of a plurality of single wire fibrous yarns as shown in Fig. 1, and a covering of fibres 66 spun around the core in the same manner that the fibres are spun around the wire core of the single wire fibrous yarn.

While I prefer to make the multiple wire fibrous yarn by using a plurality of single wire fibrous yarns as a core, it is to be understood that such a multiple yarn may be made by using a plurality of bare wires for the core, and when it is stated that a means is provided for supplying a plurality of yarns to the conveyor of the machine, it is to be understood that this means may be used for the purpose of feeding a plurality of bare wires. I prefer to make multiple wire fibrous yarns by using a plurality of single wire fibrous yarns as a core instead of bare wires for the reason that the fibres around the single wire fibrous yarn prevent the enclosed wires from chafing against each other and thus wearing out the multiple yarn. The multiple wire fibrous yarn having single wire fibrous yarns for a core forms a flexible yarn in which the wires may carry a large part of any load applied to the yarn, and in which the wires are prevented from wearing against each other.

It is also to be understood that the size, proportions and arrangement of the various parts may be varied without departing from the spirit of the invention which is not confined to the particular embodiment shown and described but is intended to include such modifications thereof as fall within the scope of the appended claims.

I claim:—

1. In a machine of the type described,

means for feeding straight fibres, a spool-holder adapted to hold a plurality of spools for feeding yarns, means for rotating said spool-holder, means cooperating with said spool-holder to form a core of parallel yarns, means for preventing the yarns from turning about their respective axes when the spool-holder revolves, and means for spinning said fibres parallel to each other spirally around said yarns.

2. In a machine of the type described, a rotatably mounted spool-holder adapted to hold a plurality of spools for feeding yarns, a wrist plate rotatably mounted on a fixed support eccentric with respect to the axis of said spool-holder, means for interconnecting said wrist plate and the spools whereby the wrist plate may cause the spools to rotate in one direction about their transverse axes while the spool-holder rotates in the opposite direction, a flier arranged to rotate in the same direction and with the same speed that the spool-holder rotates, whereby a core of parallel yarns is formed, means for feeding straight fibres and means for spinning straight fibres parallel to each other spirally around said core.

3. The method of making a rope structure, which consists in feeding yarns from a plurality of spools to form a core of parallel yarns, and spinning fibres around said core in such a manner that they lie parallel to each other spirally around the core.

4. The method of making a rope structure, which consists of feeding yarns from a plurality of spools to form a core of parallel yarns, rotating said core, spinning fibres around said rotating core in such a manner that they lie parallel to each other spirally around said core, and winding said yarns on a spool in a flier that rotates in the same direction and with the same speed as the core.

5. The method of making a rope structure, which consists in feeding yarns from a plurality of spools in such a manner that there is no torsion in the yarns, drawing the yarns together to form a core of parallel yarns, and spinning fibres around said core.

6. The method of making a rope structure, which consists in feeding yarns from a plurality of spools mounted in a spool holder, drawing the yarns together to form a core of parallel yarns, rotating said spool holder to rotate said core, rotating each of said spools so that there is no torsion in the yarns fed therefrom, and spinning fibres around said rotating core.

In testimony whereof I affix my signature.

HENRY RYDER.
